[57] CLAIM

The ornamental design for a transmission fluid transfer and cover plate for motorcycle engines, substantially as shown.

DESCRIPTION

FIG. 1 is an exploded perspective view of the two basic elements making up a transmission fluid transfer and cover plate for motorcycle engines showing my new design;

FIG. 2 is a top plan view thereof in assembled relationship;

FIG. 3 is a front side elevational view of FIG. 2;

FIG. 4 is a rear side elevational view of FIG. 2;

FIG. 5 is a left end elevational view of FIG. 2;

FIG. 6 is a right end elevation view of FIG. 2; and,

FIG. 7 is a bottom plan view of FIG. 2.

FIG. 1**FIG. 2****FIG. 3****FIG. 4****FIG. 5****FIG. 7****FIG. 6**
